UNITED STATES PATENT OFFICE.

ARLINGTON MOORE, OF NEW YORK, N. Y., ASSIGNOR TO MOORE INVENTIONS CORPORATION, OF WORCESTER, MASSACHUSETTS, A CORPORATION OF MASSACHUSETTS.

MULTIPLE-PLY SANITARY METAL CAN.

Application filed April 15, 1922, Serial No. 553,211. Renewed April 19, 1928.

My invention relates to sanitary metal containers and more particularly to metal cans adapted for containing food products and the like.

5 A feature of the invention relates to the provision of a metal can wall of substantial uniform thickness.

Another feature relates to the provision of a seal for the ends of a can in which the 10 use of gaskets is entirely eliminated, and the metal parts of the container itself are arranged effectually to prevent leakage of the contents of the container.

Other objects will appear from the following description taken in connection with the accompanying drawing in which Fig. 1 shows a side elevation of metal container with parts broken away embodying features of my invention. Figs. 2 to 7 show successive steps in the formation of the container. Fig. 8 is a transverse cross-section of the container, and Fig. 9 is an enlarged view of the joint of Fig. 8.

Referring to the drawing there is shown one embodiment of my invention comprising 25 a side wall 10 formed from a sheet of relatively thin metal, which may be formed in any desired shape, having its ends in planes substantially perpendicular to the axis of 30 the structure. As shown, a structure of cylindrical shape is provided.

The can body 10 of the present invention is made of multiple thickness in order to avoid 35 all possibility of leakage at the side seam. Such can body may be constructed on a suitable mandrel (not shown), upon which a strip of sheet metal whose width is slightly greater than the desired height of 40 the completed can, is wrapped around once to surround the mandrel forming the layer or ply 11. The metal is crimped outwardly as shown at 12 so as to be offset into a position outside of the inwardly wound portion 11 of the sheet, and the wrapping is continued 45 until one or more additional revolutions have been completed. Two layers or plies 11 and 13 are shown. If more than two layers are provided, the intermediate layers are each crimped at the portion of 50 the periphery corresponding to the leading edge portion of the sheet, and the strip is cut off of such length that it is substantially in alignment with the opposite

or leading edge of the sheet, and the outer cut edge fits into the crimp 12 of the ply 55 beneath it, as shown in Fig. 9. The various layers thus form collectively the can body 10 and the ends of the wrapped up strip may be secured in place as by means of solder. In this way there is no overlapping 60 of the opposite edge of the sheet forming the can body and a can body of uniform thickness is produced, so that all parts thereof act substantially alike in seaming on the can heads, and the metal is continuous 65 at all parts so there is no possibility of leakage as may occur at the usual side seam of a one-thickness can body. Where the can body is made of two thicknesses or convolutions, as shown herein, the metal made use 70 of is preferably of about one-half the gauge ordinarily used, as will be readily understood.

While the closure herewith described may be used only on the lid end of the can, and 75 the can bottom may be secured in place in any desired way, the top and bottom closures for the container are preferably formed in the same manner, and a description 80 of one will suffice for both.

Referring to Fig. 2, the side wall 14 of the can body 10 is provided near its end with an outwardly extending shoulder 15, the end portion 16 of the can body being outwardly displaced or expanded with 85 respect to the main portion 14 thereof a distance which is preferably substantially equal to the thickness of the can body, as shown in Fig. 2, though such displacement may be more or less than this precise 90 amount. The provision of shoulder 15 makes it possible to support and hold the can firmly during the formation of the heading seam and also serves as a stop for the lid or closure when put in place in the 95 can body.

The closure member 17 which may form either the bottom or the top of the completed can, or both, as above indicated, is provided with a marginal flange 18 which is 100 turned or flanged over so as to lie closely against the expanded portion 16 of the can body as indicated in Fig. 2 when the closure member 17 is inserted in place resting against the shoulder 15 in the can body. 105

The enlarged end portion 19 of the can

body 10 is longer than the flange 18, the relative dimensions being preferably about as indicated in Fig. 2.

The first step in forming the heading seam 5 consists in turning the outer end 19 of the expanded end portion 16 of the can body, extending beyond the lid flange 18, inwardly over the edge of said flange, first as shown in Fig. 3 and then as shown in Fig. 4, completing a turning movement of substantially 180°.

Next the parts are turned inwardly a second time from the position shown in Fig. 4 to that of Fig. 5. The bend line for this 15 operation preferably comes at substantially the middle of the lid flange 18, as shown in Fig. 5. When this is done a seam is formed about the end of the can, which comprises eight layers of metal, as shown in Figs. 5, 20 6 and 7 with the two thickness portion 19 originally forming the extreme outer edge of the can body in the center of the eight-ply seam.

This marginal seam is subjected to 25 enormous pressure applied both to the sides and to the end of the seam, bringing the parts first into the relative positions shown in Fig. 6 and finally into the positions shown in Fig. 7. The pressure applied is preferably sufficiently great to cause an actual flowing or elongation of the metal, resulting in the filling out of all open spaces in the seam with the metal to produce substantially a thick heavy ring about the can head, 35 as shown at 20, Fig. 1. In this way the parts are forced into such intimate contact that a junction is secured, equivalent in effect to the formation about the can head of a welded ring of substantial thickness and great mechanical strength.

The metal parts of ring seam 20 being in intimate contact, leakage is effectually prevented and all gaskets or linings as heretofore required are completely dispensed with.

40 It will be seen that in forming my improved seam certain portions of the metal making up the seam are turned over through an arc of as much as 270° to a complete circle of 360°, part 19 of the can body, for example, being turned over in the finished position to the extent last named to extend substantially parallel to and in the same direction as in its original position as shown in Fig. 2.

45 The construction of the joint in the can body as previously described, is such that the thickness of the side wall of the can is substantially the same at the joint as it is throughout the rest of the periphery of the can. Thus in forming the seal for the ends of the can the bending operation is the same throughout the periphery and may be performed without special precautions being taken relative to the joint. It will thus be 50 seen that an effective seal is formed which

is liquid and air tight in a simple and efficient manner.

The process of making the improved seam herein described is not claimed herein, but is claimed in my copending application 70 Serial No. 553,213, filed on even date herewith.

The claims of the present application are directed to the structure including the multiple-ply can body, which is in interseamed 75 with the can head or heads, claims for such interseamed structure not limited to the multiple-ply can body being contained in my copending application Serial No. 553, 212, filed on even date herewith. 80

An illustrative embodiment has been shown for the purpose of showing a way in which the invention may be practiced, but it is expressly understood that the scope of the invention is not to be limited thereby, 85 reference being had to the appended claims for that purpose.

I claim:

1. A metal container having a wall or body portion made up of a sheet formed into 90 a plurality of plies, the thickness of the wall being substantially uniform, and a closure member having edge portions adjacent to and in intimate contact with end portions of said wall, said adjacent portions 95 being turned over, interlocked and pressed together to seal the container.

2. A metal container having a wall or body member and an end member, the wall member being made up of a single sheet formed 100 into a plurality of layers and having a substantially uniform thickness, the adjacent edge portions of said members being in intimate contact, turned over inwardly in an interlock, and pressed together to seal the 105 container.

3. A metal container comprising a wall or body member made of a single sheet formed into a plurality of layers, the thickness of the wall being substantially uniform, and an 110 end member having edge portions adjacent to and in intimate contact with end portions of said wall, the extreme edge portion of at least one of said members being turned over through an arc of approximately 360°. 115

4. In a sheet metal can, a seamless multiple ply can body of uniform thickness, and a closure thereof, the edges of said can body and closure being united in a seam comprising two reversely turned portions of the metal of the closure and three reversely turned portions of the can body. 120

5. A metal container comprising a body made up of a single sheet formed into a plurality of layers, the thickness of the wall 125 being substantially uniform, and a closure member having edge portions adjacent to end portions of said wall member folded and refolded inwardly, the extreme edge portion of at least one of said members being 130

turned over through an arc of approximately 360°, and the seam so formed being securely pressed together to bring and retain the parts in intimate contact.

5 6. A sheet metal can, comprising a can body made up of a plurality of plies and of uniform thickness in all its parts, and a flanged head interseamed therewith by a doubly inturned seam having its parts solidly compressed together to bring the metal into intimate contact, thereby precluding leakage and dispensing with gaskets, linings and the like.

15 7. In a sheet metal can, a can body made up of a plurality of layers and of uniform thickness throughout said can body, said can body having an outwardly expanded and shouldered portion at an end thereof, a flanged closure received within the can body 20 and resting against said shoulder, and a seam uniting said can body and closure, said seam including two folds of the closure

flange and three folds of the can body all compressed under high pressure and in intimate contact.

25

8. In a sheet metal can, a body portion comprising two complete convolutions of sheet metal having their edges in substantial alignment and the body material offset between them so as to provide an uninterrupted continuous wall, said body having an expanded and shouldered end, and a closure member received in said body resting against said shoulder, and the edges of the can body and closure being united in a seam comprising two reversely turned portions of the material of the closure and three reversely turned double ply portions of the can body, the extreme edge portion of the can body being located at the central portion of 40 said seam.

In testimony whereof, I have signed my name hereto.

ARLINGTON MOORE.
